UNION OVERALLS

Filed March 7, 1928

UNITED STATES PATENT OFFICE.

CLAUDE S. KOHLER AND MAX N. KOHLER, OF NEW ORLEANS, LOUISIANA.

UNION OVERALLS.

Application filed March 7, 1928. Serial No. 259,849.

The present invention relates to improvements in overalls, and has for an object to provide an improved one-piece garment embodying a shirt with trousers attached, so that the garment will appear as an ordinary two-piece garments consisting of a separate shirt and trousers making a much neater and more dressy fit when used by work people, avoiding the unsightly appearance of the shirt working away and out of the waist band of the trousers, which always results in an ungainly, unsightly and sloppy appearance.

Another object of the invention is to produce a one-piece garment which will afford more economical means of laundering, resulting from the economy on the part of the public laundries to handle one-piece garments cheaper than those made in two or more pieces.

It is a further object of the invention to provide an improved garment of this character which is subject to adjustment and is provided with an improved adjustable tab or tabs on the waist band, which is designed to permit the user to purchase a garment a little full for him in order to permit of necessary shrinkage that takes place in all work garments where the fabric employed must, out of necessity to meet the price demand, be made up out of popular priced materials, and gather this full garment in to the requisite size.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary front elevation of an improved one-piece garment constructed in accordance with the present invention.

Figure 2 is a side view of the same.

Figure 3 is an enlarged fragmentary side view of the waist and tab portions, and

Figure 4 is a horizontal section taken on the line 4-4 in Figure 3.

Referring more particularly to the drawings 5 designates the shirt and 6 the trousers of the improved garment. The shirt is preferably of one material, for instance cambric

and of one color while the trousers are of a different material or color, so that the effect given is of a two-piece garment. However, 55 both the shirt 5 and trousers 6 are permanently joined together and for this purpose the waist band of the trousers is preferably comprised of two-sections, namely an outer section 7 and an inner section 8. Between these 60 sections, the lower edge portion of the shirt 5 is introduced and affixed, as by sewing. Lines of stitching 9 and 10 are shown as passing through respectively the lower and upper edges of both plies or sections of the waist 65 band and through the intermediate portions of the shirt material. Preferably the shirt is gathered, as indicated at 11 where it enters the waist band. This imparts to the garment a natural and attractive effect, and it also 70 serves to enable gathers to be taken at proper points in the waist band when the adjustment as to fullness of the garment is desired. It is to be noted in Figure 3 that, while gathers 11 are taken in the adjacent portions of the shirt 75 5, the trouser band is plain, smooth and ungathered except at portions shown to be engaged by the tabs 12 and 13. These tabs are provided, preferably in pairs, at the side portions of the garments, tab 12 extending toward the front and the companion tab 13 extending toward the rear of the garment. The tabs are provided with oppositely inturned adjacent edges 14 and 15 and the tabs are secured to the waist band of the trousers as 80 by the lines of stitching 16 and 17, passing through the doubled or folded portions 14 and 15, and through the waist band. At their connected portions, the tabs are preferably wide, and are shown to be as of the same width 85 as of the waist band, although this is not essential. The outer free portions of the elongated tabs are reduced in width and form long, narrow tongues 18 and 19. In the body portions of the tabs are provided button 90 holes 20 and 21 and in the outermost portions of the tongues 18 and 19 are provided button holes 22 and 23. The button holes 20 and 21 are preferably elongated in a vertical direction, and they are preferably offset from one 95 another at different horizontal positions; while the outer button holes 22 and 23 are with advantage elongated in a horizontal direction,

The button holes 20 and 21 are arranged to be engaged by buttons 24 and 25 sewed or otherwise secured to the waist band of the garment. In like manner other buttons 26 5 and 27 are sewed, or otherwise fastened to the garment band and designed to be engaged by the button holes 22 and 23 respectively.

In use, when the tabs are fully buttoned, as shown in Figure 3, gathers 28, 29, 30 and 31 10 are produced in the waist band and the fullness of the waist band is to this extent taken up. By undoing all four buttons at each side of the garment, if duplicate sets of the tabs are provided at opposite sides, the garment may be let out to its complete fullness. 15 If the garment is only to be taken in one notch or step, the button 24 may, for instance, be engaged with the button hole 20 of the tab 12 and the remaining button holes left disengaged or unoccupied. By buttoning the tab 13 to the button 25, a second notch or step may be taken in; and in this way the garment band is subject to numerous adjustments in 20 circumferential length, which will enable the 25 garment to accommodate itself, when new to a wearer, who is obliged, on account of expected shrinkage in the garment, to purchase originally a garment much too large for him. By the use of the improved tabs the neat and 30 attractive appearance of a well fitting garment may be had from the outset.

It will be noted that the button hole 20 is spaced from the line of stitching 16, which connects the tab 12 to the trousers waist band, 35 a distance shorter than the distance between the button 24 on the waist band and the stitching 16; in other words, when the button 24 is disengaged from the button hole 20, the gathering 29 may be pulled out, the button 24 taking a position to the left of that occupied in 40 Figure 3. The distance between the button holes 20 and 21 of the same tab is less than the distance between the buttons 24 and 26, even when the button 24 is engaged with the button 45 hole 20. This provides a fullness of material in the waist band between the two buttons 24 and 26, so that when the latter button is engaged in the button hole 22, as shown in Figure 3, the gathering 28 takes place in the 50 waist band and the circumferential length of the waist band is to this extent reduced. After laundering and shrinkage, the button 26 may be disengaged and the waist band stretched out giving the garment greater fullness. 55 The narrow tongues 18 and 19 will admit the fingers upon both sides thereof and enable same to be easily manipulated in engaging and disengaging the buttons 26 and 27, and the elongation of the outer button 60 holes in the horizontal, which is also the direction of elongation of the tongues, enables the buttons to be engaged by an up or down movement of the free ends of the tabs which will be found easiest to the fingers of the 65 user.

However, when the tongues are disengaged and rolled away from the waist band for the purpose of getting at and disengaging the buttons 24 and 25, the natural rolling motion of the tabs will be most effective upon the vertical elongated button holes 20 and 21 which can thereby be easily engaged and undone. The elongated abutting inner fixed ends of the wide portions of the two-tabs reinforces and strengthens one another and the abutting arrangement of the tabs and the extension of the same in opposite directions makes for a neat appearance in the garment. 70

It is obvious that various changes and modifications may be made in the details of construction and design of the above specifically described embodiment of this invention without departing from the spirit thereof, such changes and modifications being restricted only by the scope of the following claims. 75

What is claimed is:—

1. A union garment comprising a shirt, trousers having a waist band of inner and outer sections clamped about, and secured to, the lower gathered portion of said shirt, and a pair of tabs secured at each side of said waist band and each composed of inner, wide portions and outer narrow elongated tongues, the inner wide portions abutting together and having oppositely overlapped end portions folded in against the trouser band, lines of stitching passing through said tabs and the folded over end portions and also through the waist band, said tabs having relatively offset vertically elongated button holes upon the inner portions of the tabs and having horizontally elongated button holes at the outer tip portions of the tongues, and pairs of buttons secured to the waist band for engaging said button holes, a pair for engaging each tab, the inner buttons being spaced on the waist band from the points of attachment of the tabs at greater distance than the inner button holes from the same point of attachment, each pair of buttons being spaced apart on the waist band at greater distance than between corresponding button holes on the tabs and tongues even when the inner buttons are engaged with the inner button holes. 90

2. An improved union garment comprising a shirt, trousers having a waist band affixed to the shirt, and a pair of tabs secured at each side of said waist band and each composed of inner, wide portions and outer narrow elongated tongues, the inner wide portions abutting together and having oppositely overlapped end portions folded in against the trouser band, lines of stitching passing through said tabs and the folded over end portions and also through the waist band, said tabs having relatively offset vertically elongated button holes upon the inner portions of the tabs and having horizontally elongated button holes at the outer tip portions of the tongues, and pairs of buttons secured to the 100 105 110 115 120 125 130

waist band for engaging said button holes, a pair for engaging each tab, the inner buttons being spaced on the waist band from the points of attachment of the tabs at greater distance than the inner button holes from the same point of attachment, each pair of buttons being spaced apart on the waist band at

5 greater distance than between corresponding button holes on the tabs and tongues even when the inner buttons are engaged with the 10 inner button holes.
